G. M. RYAN

ARMOR PIERCING PROJECTILE

Filed April 1, 1924

UNITED STATES PATENT OFFICE.

GEORGE M. RYAN, OF EMO, ONTARIO, CANADA.

ARMOR-PIERCING PROJECTILE.

Application filed April 1, 1924. Serial No. 703,448.

To all whom it may concern:

Be it known that I, GEORGE M. RYAN, a citizen of the United States, residing at Emo, in the Province of Ontario and 5 Dominion of Canada, have invented certain new and useful Improvements in Armor-Piercing Projectiles, of which the following is a specification, reference being had to the accompanying drawings.

10 This invention relates to armor piercing projectiles and more particularly to that type of shell having a drill type penetrator at the entering end thereof.

An important object of the invention is 15 to provide in this type of construction a shielding nose for the projectile formed of soft metal which protects the penetrating end from damage, and in that type of shell in which the penetrator head is given a 20 limited longitudinal movement for the purpose of detonating an explosive charge carried by the shell; for the further purpose of preventing contact with the penetrator which would cause such movement.

25 A still further object of the invention is to provide a shell of this character which may be very cheaply and readily produced and which is capable of carrying a relatively large charge of high explosive if so desired.

30 A still further object of the invention is to provide in a shell of this type a sufficient protection for the penetrator to prevent tearing and damage of the rifling of the guns during passage of the shells there- 35 through.

These and other objects I attain by the construction shown in the accompanying drawings, wherein for the purpose of illustration is shown a preferred embodiment of my invention and wherein:—

Figure 1 is a side elevation showing an explosive form of shell constructed in accordance with my invention;

Figure 2 is a section on the line 2—2 of 45 Figure 1;

Figure 3 is a fragmentary sectional view of a solid type of shell constructed in accordance with my invention;

Figure 4 is a section on the line 4—4 of 50 Figure 3.

Referring now more particularly to the

drawings, the numeral 10 indicates the body of the shell provided adjacent its rear end with a rifling band 11 of any suitable construction. The forward end or nose of the shell is tapered, as at 12, and truncated, as at 13. Axially of the shell in this truncated end a recess is formed of the same diameter as the penetrator 15 which is to be employed. This penetrator is preferably in the form of a high-grade drill structure which is highly tempered. The rear end of this drill seats against a plate 16, the shank 17 of the drill being extended through the plate at the center thereof. In the form shown in Figure 3 this plate seats against shoulders 18 formed by the juncture of the lower end of the bore 14 with a reduced continuation thereof, indicated at 19, this reduced continuation being preferably square in cross section to conform to the shaping of the drill shank.

In the form shown in Figures 1 and 2, wherein the shell is of the high explosive type and has an interiorly formed cavity 20 for the reception of high explosive, the cavity 14 is made of greater depth than in the form just described and has seated therein a casting 21 forming a socket for the drill shank. In this form the casting has a central bore 22 conforming to the shape of the drill shank and the front face of this casting forms a seat for springs 23 extending between this face and the plate 16 and forming a cushioning spring for the penetrator or drill.

The lower end of the bore 14 communicates with a reduced axial bore 24 communicating with the adjacent end of the explosive receiving cavity 20, this reduced bore 24 forming a guide for a detonator pin 25. In the adjacent end of the explosive chamber a detonator cap 26 is arranged and the head of the pin 25 is arranged in the path of movement of the shank and more particularly in the path of movement of a reduced extension 27 of the shank for engagement thereby when the drill or penetrator is forced rearwardly by contact of the shell with the target. In order that movement of the pin 25 may be prevented until the penetrator moves rearwardly, the for-

ward or head end of this pin is embedded in soft lead or the like, as indicated, to hold the same firmly in position.

In each form of the shell it will be noted that the tapering of the forward end of the shell formed upon the body of the shell, as indicated at 12, is continued by a solid mass of soft metal 28 such as lead or the like in which the projecting end of the penetrator 10 is embedded. This covering 28 effectually prevents movement of the penetrator with relation to the shell under any ordinary circumstances and at the same time serves to shield the rifling of the gun with 15 which the shell is employed against contact with the penetrator and to further prevent disastrous effects to clothing, woodwork and the like when contact of the penetrator is had therewith.

20 The use of the first form of shell described will be obvious, this consisting merely of an armor piercing shell to which rotation is applied to the rifling band. Particular attention is directed to the fact that 25 this rifling band is located at the rear end of the shell so that an impulse applied thereto by a fired charge will be continued to the rearwardly of the muzzle of the gun thereby assuring a maximum rotation of the shell. Upon contact 30 of the shell with the target the soft nose will be crushed exposing the penetrator or drill which, through the rotative action of the shell, will tend to worm its way into the obstruction. It is well known that a 35 shell can readily pass through an opening once formed no matter whether this opening be smaller than the body of the shell or not.

In the second type of shell disclosed the action is similar to that of the first shell except that the penetrator before coming into 40 action moves rearwardly until it comes against the front face of the casting 21. During this rearward movement it moves the pin 25 to detonate the contained explosive 45 charge. The period of detonation can, of course, be regulated so that this detonation takes place after the shell has pierced the objective.

The cushioning springs 23 soften the impact of the drill which is, of course, of hardened steel at its end, thus preventing shattering of the drill. They further assist in preventing rearward movement of the drill portion which would tend to operate the 55 detonator. Positive means are provided, however, for preventing such rearward movement comprising frangible braces 29 extending between the plates 16 and the plate arranged upon the front face of the 60 casting 21. These braces may be of any suitable material as, for example, wood and under impact of the shell are designed to crush permitting rearward movement of the drill until it comes to a solid rest. Since the 65 structures hereinbefore set forth are capable

of a certain range of change and modification without materially departing from the spirit of my invention, I do not limit myself to such specific structures except as hereinafter claimed.

I claim:

1. In an armor piercing shell, a shell having a body provided upon its periphery at one end with a rifling band and having the opposite end thereof provided with a truncated taper, a penetrator drill axially embedded in the last named end of the shell, and a covering of soft metal in which the projecting end of the penetrator drill is embedded, comprising a continuation of the taper of the body of the shell.
2. In an armor piercing shell, a shell having a body provided upon its periphery at one end with a rifling band and having the opposite end thereof provided with a truncated taper, a penetrator drill axially embedded in the last named end of the shell, and a covering of soft metal in which the projecting end of the penetrator drill is embedded, comprising a continuation of the taper of the body of the shell, said penetrator drill having a shank preventing rotation thereof with relation to the shell.
3. In an armor piercing shell, a shell having a body provided upon its periphery at one end with a rifling band and having the opposite end thereof provided with a truncated taper, a penetrator drill axially embedded in the last named end of the shell, and a covering of soft metal in which the projecting end of the penetrator drill is embedded, comprising a continuation of the taper of the body of the shell, said penetrator point being mounted for limited shifting movement longitudinally of the shell and being held against such movement by the soft metal point.
4. In an armor piercing shell, a shell having a body provided upon its periphery at one end with a rifling band and having the opposite end thereof provided with a truncated taper, a penetrator drill axially embedded in the last named end of the shell, a covering of soft metal in which the projecting end of the penetrator drill is embedded, comprising a continuation of the taper of the body of the shell, said penetrator point being mounted for limited shifting movement longitudinally of the shell and being held against such movement by the soft metal point, an explosive charge in the body of the shell, and means whereby axial movement of the penetrator of the shell upon impact of the shell with the target explodes said charge.
5. In an armor piercing shell, a shell having a body provided upon its periphery at one end with a rifling band and having the opposite end thereof provided with a truncated taper, a penetrator drill axially em-

bedded in the last named end of the shell, a shell and being held against such movement covering of soft metal in which the projecting end of the penetrator drill is embedded, comprising a continuation of the 10
5 taper of the body of the shell, said penetrator point being mounted for limited shifting movement longitudinally of the

In testimony whereof I hereunto affix my signature.

GEORGE M. RYAN.
